UNITED STATES PATENT OFFICE.

JOHN NEELY, OF LAPEER, MICHIGAN.

BLEACHING-GAS GENERATOR.

1,145,609.

Specification of Letters Patent. Patented July 6, 1915.

Application filed October 16, 1914. Serial No. 867,044.

To all whom it may concern:

Be it known that I, JOHN NEELY, a citizen of the United States of America, residing at Lapeer, in the county of Lapeer and State of Michigan, have invented certain new and useful Improvements in Bleaching-Gas Generators, of which the following is a specification, reference being had therein to the accompanying drawings.

10 This invention relates to bleaching-gas generators, wherein a bleaching agent is generated or compounded and conveyed to a bolting machine or flour chute, onto a point of contact with flour whereby the same can 15 be bleached.

The object of my invention is to provide a simple, durable and inexpensive generator wherein novel means is employed for automatically controlling the process by which 20 a bleaching agent is liberated or set free.

The above and other objects are attained by a generator that will be hereinafter specifically described and then claimed, and reference will now be had to the drawing, 25 wherein—

Figure 1 is an elevation of one side of the generator; Fig. 2 is a similar view of the other side, partly broken away and partly in section, and Fig. 3 is a plan of the generator.

30 A generator in accordance with this invention comprises a rectangular casing having a base 1, side walls 2 and 3 and end walls 4 and 5 supporting a top plate 6. The side walls 2 and 3 are extended beyond the

35 end wall 5, the extension being of less height than the side walls to support an auxiliary top plate 7. The extensions of the side walls 2 and 3 are connected by an auxiliary end wall 8 having a hinged door 9, and said

40 door, the auxiliary top plate 7, the auxiliary end wall 8, and the extension of the walls 2 and 3, coöperate in providing a rectangular generating chamber 10 at an end of the casing.

45 In the upper part of the casing and connecting the side walls 2 and 3 are horizontal and vertical partitions 11 and 12 and these partitions are connected by a longitudinal partition 13. These partitions pro-

50 vide communicating compartments 14 and 15 and the compartment 14 communicates with the generating chamber 10 through the medium of an opening 16 in the end wall 5 of the casing.

55 The side walls 2 and 3 at the end wall 4, are provided with bearings 17 for a trans-

verse driven shaft 18. This shaft has one end thereof provided with a pulley 19 and a flanged belt wheel 20, while at the opposite end of the shaft is a large flanged belt wheel 21. It is through the medium of the pulley 19 that the shaft 18 can be driven by a motor or from a suitable source of power.

Journaled in the side walls 2 and 3 and extending transversely of the compartments 65 14 and 15 is a fan shaft 22 having a fan or bladed wheel 23 within the compartment 15 and a small flanged belt wheel 24 at the outer side of the wall 2. A belt 25 is trained over the belt wheels 21 and 24 whereby the 70 fan 23 can be driven within the compartment 15.

The side wall 3 supports a revoluble shaft 26 and mounted upon said shaft is a large flanged belt wheel 27 over which is trained 75 a belt 28 that passes around a small belt wheel 20. The belt wheel 27 is provided with a pivoted bar 29 having an end thereof adjustably connected to a slotted web 30 of the wheel 27. The bar 29 supports a wrist 80 pin 31 and connected to said pin is a pitman 32.

Mounted upon the top of the auxiliary plate 7 is a feeding device, comprising a base plate 33, sets of bearings 34 and shafts 35 85 and 36. These shafts support a train of gears 37 and the shaft 35 has an end thereof provided with a ratchet wheel 38 and a ratchet arm 39.

The ratchet arm 39 has the outer end 90 thereof pivotally connected, as at 40 to the pitman 32 and said ratchet arm is provided with a gravity pawl or dog 41 normally engaging the ratchet wheel 38, whereby said ratchet wheel and the shaft 35 can be intermittently moved by the driven belt wheel 27.

One end of the shaft 36 has a gravity dog 42 normally engaging the ratchet wheel 38 to prevent a counter clockwise movement of the shaft 35 as the gravity pawl 41 moves 100 over the same to obtain a fresh grip upon the ratchet wheel. The opposite end of the shaft 36 is provided with a grooved wheel 43 confronting a wheel or roll 44 revolvably supported by a resilient arm 45 connected 105 to the base plate 33. The wheels 43 and 44 constitute feed rolls for a metallic rod or galvanized wire 46, which is guided through an opening 47 in the auxiliary top plate 7 to enter a receptacle 48 in the generating chamber 10 of the machine. The receptacle 48 is graduated and is adapted 110

to contain chemicals, which when combined with the metallic element, as the rod 46, liberates a bleaching gas or agent, as nitric oxid, that is drawn through the opening 16 5 into the compartments 14 and 15 by the fan 23 and is conveyed to a desired point by a conduit 49 communicating with an opening 50 in the top plate 6. Another opening 51 10 in the side wall 2 admits air to the generating chamber 10 of the machine.

From the foregoing it will be observed that the feeding mechanism above the generating chamber 10 controls the use of the bleaching fluid in the receptacle 48 and the 15 process by which a bleaching agent is set free. The feeding of the metallic element 46 into the bleaching fluid can be regulated by adjusting the wrist pin bar 29 of the belt wheel 27, and the operation of the generator 20 can be timed whereby a proper proportion of bleaching agent will be liberated for a given amount of flour.

It is thought that the operation and utility 25 of the generator will be apparent without further description, and while in the drawing there is illustrated a preferred embodiment of the invention, it is to be understood that the structural elements are susceptible to the variations and modifications as fall 30 within the scope of the appended claim.

What I claim is:—

In a flour bleaching gas generator, a cas-

ing having a generating chamber at one end thereof and communicating compartments therein, a receptacle in said generating chamber adapted to contain chemicals, an intermittently actuated feeding mechanism above the chamber of said casing and adapted to feed and guide galvanized wire into the fluid within said generating chamber to 40 liberate nitric oxid, a fan shaft through the said compartments in said casing, a fan on said shaft in one of said compartments adapted to draw the bleaching agent from the generating chamber into the fan compartment and force the same to a point remote from said generator, a driven shaft supported by said casing at the end opposite the generating chamber adapted to operate said fan shaft, a revoluble wheel at the opposite side of the generator adapted to have movement imparted thereto by said driven shaft at one side of said generator, an adjustable pivoted bar carried by said wheel, and a pitman connected to said bar and adapted to operate said feeding mechanism.

In testimony whereof I affix my signature in presence of two witnesses.

JOHN NEELY.
